UNITED STATES PATENT OFFICE.

PERCY J. CALLOWHILL, OF PROVIDENCE, RHODE ISLAND.

DESIGN FOR A BRACELET LINK.

Application filed March 28, 1927. Serial No. 21,367. Term of patent 7 years.

To all whom it may concern:

Be it known that I, PERCY J. CALLOWHILL, a subject of the King of Great Britain, a resident of Providence, in the county of Providence and State of Rhode Island, have invented a new, original, and ornamental Design for a Bracelet Link, of which the following is a specification, reference being had to the accompanying drawings, forming part thereof.

Fig. 1 is a plan view of the bracelet link showing my new design, and

Fig. 2 is a top edge view thereof.

I claim:

The ornamental design for a bracelet link, as shown.

In testimony whereof I have signed my name to this specification.

PERCY J. CALLOWHILL.
